UNITED STATES PATENT OFFICE.

ENID BOWERS, OF PRESCOTT, ARIZONA, ASSIGNOR TO KERVIN R. PHILLIPS, OF PRESCOTT, ARIZONA.

DESIGN FOR A BOOK END.

Application filed March 19, 1923. Serial No. 5,513. Term of patent 14 years.

To all whom it may concern:

Be it known that I, ENID BOWERS, a citizen of the United States of America, and a resident of Prescott, Arizona, have invented a new and original Design for Book Ends, of which the following is a specification, reference being had to the annexed drawing, forming a part thereof.

In the accompanying drawing:

Fig. 1 is a front elevation of a book-end embodying my new design; and

Fig. 2 is a side elevation.

What is claimed is:—

The ornamental design for a book-end, as shown.

In testimony whereof, I have signed this specification.

ENID BOWERS.
